YIELDABLE PLASTIC HOUSING FOR A CABLE SPLICE

Raymond F. Piasecki, Hazlet, N.J., assignor to The
Thomas & Betts Co., Incorporated, Elizabeth, N.J.,
a corporation of New Jersey

Filed Mar. 22, 1965, Ser. No. 84,381

Term of patent 14 years

(Cl. D26—1)

FIGURE 1 is a perspective view of a yieldable plastic housing for a cable splice showing my new design, in closed condition;

FIGURE 2 is a perspective view thereof in open condition;

FIGURE 3 is a fragmentary side elevational view of the housing in closed condition on a cable, the cable being indicated fragmentarily in broken lines; and

FIGURE 4 is an enlarged fragmentary sectional view to the detail of one area of the housing.

I claim:

The ornamental design for a yieldable plastic housing for a cable splice, as shown and described.
